UNITED STATES PATENT OFFICE.

BRYAN D. PINKNEY, OF CLEVELAND, OHIO, ASSIGNOR TO THE LOEW MANUFACTURING COMPANY, OF CLEVELAND, OHIO, A CORPORATION OF OHIO.

BOTTLE-CLEANING APPARATUS.

1,110,817.

Specification of Letters Patent.

Patented Sept. 15, 1914.

Application filed October 2, 1908, Serial No. 455,792. Renewed May 18, 1914. Serial No. 839,438.

To all whom it may concern:

Be it known that I, BRYAN D. PINKNEY, a citizen of the United States, residing at Cleveland, in the county of Cuyahoga and State of Ohio, have invented a certain new and useful Improvement in Bottle-Cleaning Apparatus, of which the following is a full, clear, and exact description, reference being had to the accompanying drawings.

My invention relates to bottle-cleaning apparatus, and its object is to provide an automatically operated machine of large capacity which will thoroughly cleanse and rinse bottles after they have been placed on an intermittently operating carrier without further attention on the part of the operator.

The object of the invention generally is to improve the construction and operation of machines of the type referred to.

Further objects of the invention are to provide a machine of this character which is adaptable for large and small bottles; which will subject the bottles successively to the action of side, bottom and side brushes while brushing the insides of the bottles and will thereafter rinse the insides of the bottles; to provide a construction of internal brushing mechanism whereby injury to the brushes is prevented or minimized; also to provide an improved construction of automatically-operating bottle-gripping mechanism which will center the bottle and will support the same during the operation of the bottom brushes and will automatically open a sufficient distance to allow the operation of the side brushes; also to provide an improved construction of clamping mechanism for the bottoms of the bottles.

Generally speaking, the invention may be defined as consisting of the combinations of elements embodied in the claims hereto annexed and illustrated, in one embodiment, in the drawings forming a part hereof wherein—

Figure 1 represents a top plan view of a machine constructed in accordance with my invention, some of the body clamps or grippers being omitted; Fig. 2 represents a side elevation of the machine shown in Fig. 1, with parts of the casing broken away to reveal the construction of parts; Fig. 3 represents a vertical sectional view taken on the line 3—3 of Fig. 1, looking in the direction of the arrows; Fig. 4 represents a view similar to Fig. 3 taken on the line 4—4 of Fig. 1

and looking in the direction of the arrows; Fig. 5 represents a horizontal sectional view taken on the line 5—5 of Fig. 3; Fig. 6 represents a sectional detail taken on the line 6—6 of Fig. 3; Fig. 7 represents a detail in elevation of the connections for driving the carrier intermittently; Fig. 8 represents an enlarged detail, partly in section and partly in elevation, of the brush carrier, one of the brush spindles and its associated parts, and the bottle holder and bottom brush; Fig. 9 represents a top plan view of a bottom brush and its associated parts; Fig. 10 a detail, partly in section and partly in elevation, of one of the bottom clamps for the bottles, together with the associated parts; Fig. 11 represents a sectional detail of the bottom of one of the brush carriers; Fig. 12, a plan view of one of the bottom clamps or grippers; Fig. 13, a plan view of one of the spindle carriers; Fig. 14, a vertical sectional detail of said carrier; Fig. 15, a sectional detail corresponding to the line 15—15 of Fig. 3; Fig. 16, a sectional detail showing the connections for raising and lowering the various devices which operate upon the bottoms of the bottles; Fig. 17, a sectional detail corresponding to line 17—17 of Fig. 3; Fig. 18, a sectional detail of one of the rinser-spindles and its carrier; Fig. 19, a top plan view of the rinser spindle; and Fig. 20 a rear elevation of a portion of the bottle carrier.

Describing the parts by reference characters, 1 denotes a base or frame on which the various parts of my apparatus are supported. This frame is provided with a pair of vertically extending side members 2, a cross member 3, intermediate between the top and bottom of the frame, and an upper cross member 4. Member 3 is preferably formed as a casting having a downwardly projecting portion adapted to form journals for shafts which will be described hereinafter. The upper member 4 is extended to provide the top of a casing in which the bottles inserted into the apparatus are brushed and rinsed. This extension of the upper member is denoted at 5 and a corresponding bottom 6 is provided, spaced from 5 a suitable distance.

7 denotes the casing proper, which is interposed between 5 and 6. The casing 7 is preferably fitted between grooves provided in the top and bottom members 5 and 6 re-

spectively. These grooves are of considerable depth and the casing is detachably secured in place by means of buttons 8 mounted on the casing and adapted to engage the 5 lower outer edge of the member 5. At its sides, casing 7 is open to permit the passage therethrough of the bottle carrier and the bottles thereon.

My apparatus may be driven from any 10 suitable source of power, a motor 9 being shown for this purpose and being mounted on top of the member 4, preferably by means of a plate 10 detachably secured to the member 4.

15 The motor 9 is provided with a shaft 11 having thereon a pulley 12, indicated in dotted lines on Fig. 3. 13 denotes a large pulley similarly indicated and mounted on a shaft 14 and connected by a belt 15 with 20 pulley 12. Shaft 14 is journaled in a part of the frame and is provided with a bevel gear 16 meshing with a similar gear 17 on a vertical shaft 18. This shaft is provided with a gear 19 rigid therewith and meshing 25 with a gear 20 rigid with a hub 21 which is loosely mounted on the shaft 22. 23 denotes a smaller gear on the hub 21 meshing with a larger gear 24 which is rigid with the hub 25 of a smaller gear 26. The last mentioned gear meshes with a larger gear 27 which is rigid with shaft 22. Shaft 22 is provided at its lower end with a bevel gear 28 meshing with a similar gear 29 on a horizontal crank and cam shaft 30, which shaft 35 is mounted in the side frames 2. Shaft 30 is provided at one end thereof with a bevel gear 31 meshing with a similar gear 32 on a shaft 33 which is carried by bearings projecting from opposite ends of one of the side 40 members of the main frame. This shaft is provided with a bevel gear 34 meshing with a similar gear 35 on a vertical shaft 36. The shaft 36 extends vertically alongside of the frame of the machine and has at its upper end 45 a sprocket 37 for a chain 38, by means of which and a similar sprocket 39 the motion of the shaft 36 is transmitted to a shaft 40. The shaft 40 is for the purpose of rotating the various devices which operate upon the bottoms and outsides of the bottles. It is provided below the cover plate 5 with a gear 41 meshing with a similar gear 42 on the spindle 43 of the bottom brush. Gear 42 meshes with a similar gear 55. 44 on the spindle 45 of a bottom clamp. Gear 44 meshes with a similar gear 46 on the spindle 47 of the second bottom brush of the series. It will be apparent that, by the rotation of shaft 40, through the chain and 55 sprocket connection described before, the various bottom clamps and bottom brushes will be rotated and that each of the devices which operates upon the bottoms of the bottles will be turned in a reverse direction 60 from that of the preceding device. Gear 42

is also in mesh with a smaller gear 48 which meshes with an idle gear 49, said idle gear meshing in turn with a pinion 50 on the spindle 51 which operates one of the brushes for the outside of the bottles. Gear 48 also 70 meshes with an idle gear 52 and the latter gear meshes with a pinion 53 on the spindle 54 of a second brush which operates upon the outside of the bottles. By the arrangement of gears, the adjacent surfaces of the 75 bottles and their side brushes turn in opposite directions, thereby efficiently brushing the outsides of the bottles.

The bottom plate 6 of the casing is provided with apertures in which are mounted 80 gear hubs 55, said gear hubs being adapted to receive the brush sleeves 56. The gear hubs are mounted in a journal casting 57, as are also the lower ends of the brush shafts 51 and 54. The internal brush spindles and 85 the rinser spindle are driven from the shaft 18 by means of a large gear 58 on said shaft meshing with a pair of pinions 59 and 60 mounted on shafts 61 and 62 respectively, said pinions being formed on the hubs of 90 gears 63 and 64 respectively. Gear 64 meshes with the gear 65 on the brush spindle 66, also with the gear 55^a on hub 55, the last mentioned gear being on the brush spindle 67. Gear 63 also meshes with gear 55^a 95 and with the gear 68 on the brush spindle 69. From this construction it follows that the revolution of the shaft 18 causes the brush spindles 66, 67 and 69 to rotate in the same direction. The rinser spindle 70 is not 100 rotated, and hence no gear is provided for the same.

The bottles are mounted on a bottle carrier, which will be described at length hereinafter, but which consists generally of a 105 pair of chains carrying bottle-supporting brackets, each bracket having a pair of grippers for the body of the bottle and a mouth support. These chains and the bottles carried thereby are given an intermittent movement by the following construction:—The shaft 36 drives a short shaft 71 through what is known to the trade as a "Geneva movement", the same being illustrated in Figs. 2 and 7. Shaft 71 is provided with a 110 pinion 72 meshing with a gear 73 on a shaft 74. The last mentioned shaft is provided with a pair of sprocket wheels 75, 76. By means of the Geneva movement, an intermittent movement is imparted to the shaft 115 71, which movement is transmitted to the shaft 74. The carrier travels in an elliptical orbit and is arranged in a horizontal plane. The sprocket shaft 74 is supported at one side of the apparatus and a similar shaft 77 120 is journaled at the opposite side of the apparatus and is provided with sprocket wheels 78 and 79 corresponding to the wheels 75, 76, respectively.

The bottle-carrier will now be described 130

- in detail. This carrier comprises a special construction of chain which supports the grippers for the bodies of the bottles and the bottom supports for the bottles. This chain is illustrated in detail in Figs. 8, 12, and 20 and comprises in effect an upper and a lower chain which are connected and driven by means of the brackets which carry the bottle grippers and mouth supports. 5 Each bracket comprises a casting 80, which in shape resembles the letter J, and has its lower portion provided with a vertically extending aperture for the reception of a bottle-mouth support 81. This support has a neck 82 adapted to fit within said aperture and may be secured in place by means of a set screw, 83. The mouth support or clamp flares upwardly and outwardly to receive and form a snug fit with the mouths of the bottles that may be applied thereto. At the upper end each of the castings 80 is provided with a rearwardly projecting lug or plate 84, which lug or plate provides a support and a guide for the links by which 10 the bottle-gripper may be opened and closed as well as a support for such gripper. Each casting 80 is also provided at opposite ends thereof with apertures 86 for attachment to the links by means of which the brackets are connected with the next brackets in the series. 87 and 88 denote rollers which are mounted respectively above and below the lugs 85, 85^a and which are engaged by the teeth on the sprocket wheels 75, 76 and 78, 15 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

with a rubber lining 107 adapted to engage the bottom of the bottle. The hub 105 is connected with the shaft 40 (assuming that the clamp shown in Fig. 10 is the first one in the series of bottom clamps). This shaft is provided with a long key-way 108 by means of which it is secured to its gear 41, previously referred to, in such manner as to permit the shaft and clamp to be reciprocated through the gear without disturbing the relation between said gear and its driven gear 42. For the purpose of rinsing the outside of the bottle while it is subjected to the first and third operations of cleaning, each bracket 100 is provided with a curved pipe or nozzle 109 which is provided with a flexible connection 110 communicating with a supply pipe 110^a. Pipe 109 curves downwardly into position to direct the water against the outer surface of the bottle near the bottom thereof, as the bottle is rotated by means of the shafts 40 and 45. During the first and third operations referred to, the outside of the bottle is brushed by means of vertical brushes 111, 112 mounted respectively on the shafts 51 and 54. These brushes are of such shape as to conform to the outside of a bottle and are rotated by means of the train of gearing hereinbefore described. The bottom plate 6 of the casing is provided with an upturned flange making it in effect a trough, and the trough thus formed is provided with a drain pipe 113 (see Fig. 2).

Assuming that the carrier travels to the right in Fig. 2, the second operation to which the bottles will be subjected is the operation of brushing the bottoms thereof. The bottom brush is mounted in a bracket 100^a, similar to the brackets for the bottom clamps but having a larger aperture or shell for the reception of the bottom brush. This brush comprises the shaft 43 and the brush head 114. This brush head is mounted with-in a sleeve 115 and said sleeve is provided with a vertical hub 116 projecting upwardly through a cap 117 which rests on top of the shell 100^b of bracket 100^a. The lower end of sleeve 115 projects outwardly below the bracket 100^a, and a ball-bearing 118 is formed between a flange on the lower edge of said sleeve and the shell of said bracket. By means of a pin 119 extending through the shaft, through hub 116 and through the corresponding hub on the cap 117, the brush, the sleeve and the cap are caused to rotate together by the rotation imparted to the brush shaft 43. As will appear more particularly from Fig. 8, a space is provided between the sleeve 115 and the surrounding part or shell of the bracket 100^a. Also a space is provided between the top of sleeve 115 and the bottom of the cap 117. A flexible pipe 120 supplies water from the pipe 110^a to the space between the sleeve 115 and

the shell of bracket 100^a and thence through ports 121, 122 to the bottom brush. Ports 122 are for the purpose of lubricating the bearing between cap 117 and the shell 100^b.

The shaft 45 is also provided with a bottom clamp, similar in all respects to the one shown in Fig. 10 and needs no separate description. Shaft 47 is provided with a brush similar to that shown in Figs. 3 and 8 and hence needs no separate description.

The mechanism for washing the interior of the bottles comprises generally a frame or cross head mounted upon guide rods or standards, with means for reciprocating the same toward and from the bottle carrier, and means for automatically disconnecting from said frame or cross-head one or more of the devices which operate upon the interior of the bottles when said device or devices have approached a predetermined distance with reference to the bottoms of the bottles, whereby my apparatus is adapted for various sizes of bottles and will operate without breaking said bottles. In the embodiment of my invention shown herein, there are three brushes for brushing the interior of the bottles. These brushes may be of any suitable design, such, for example, as the well known rubber tube type with a split end. In Figs. 3 and 8, said brushes are shown, and each comprises a brush spindle 66, 67, or 69, each having an elongated key-way as 123 therein by means of which it is keyed to its corresponding gear. The brush proper 124, when the crosshead or frame is at its lowermost position, is within the brush sleeve 56. The upper end of this sleeve is frusto-conical in shape, as shown at 56^a, for a purpose to be described hereinafter. The use of the elongated key-way 123 permits the brush spindle to be reciprocated and at the same time maintains its connection with its gear. The various brush sleeves are mounted in a plate 125 which extends longitudinally of the frame.

126 denotes the frame or crosshead to which reference has been made hereinbefore (see Figs. 5 and 8). This crosshead is mounted on guide rods 127 and is operated by means of levers 128 connected by links 129 to opposite ends of the crosshead and mounted on a rock shaft 130 which is journaled in the opposite ends of the frame. Levers 128 are connected by means of cranks 131 with the shaft 30. From this construction it will be apparent that, with every revolution of the shaft 30, the levers 128 and crosshead 126 will be reciprocated.

For the purpose of accommodating the apparatus to various sizes of bottles and preventing the breaking of the bottles by the impact of the brush or rinser spindles against the bottoms of the same, I provide a breakable connection between the crosshead and each brush and rinser spindle, with

means for automatically breaking such connection when the said spindles or any of them approach within a predetermined distance of the bottoms of the bottles. The 5 breakable connection between the crosshead and the brush and rinser spindles will now be described. As this connection is the same for each spindle, a detailed description of one of such connections will be sufficient 10 for all. 132 denotes a brush carrier for each of the aforesaid spindles. This brush carrier is guided upon suitable guide rods and carries in addition to its spindle a trip rod 133 which projects upwardly therefrom and 15 through the plate 125. This trip rod projects downwardly through a guide on the brush carrier and is at its lower end supported by a curved lever 134 which is provided with a pair of upwardly projecting 20 forks 135 mounted on a shaft 136. The same lever 134 has a projection 137 which normally engages a projection 138 on the brush carrier frame. The shaft 136 extends through and is carried by the upper end of a 25 trip-lever or latch 139, which is pivoted at 140 between a pair of jaws formed on the brush-carrier frame. This trip lever is provided with a vertically extending recess 141 in the rear face thereof, said recess having 30 at the top an abrupt shoulder 142 and at the bottom a similar elongated shoulder 143. The crosshead is provided with pins 144, one for each brush carrier. These pins normally enter the recesses 141 and on the 35 up-stroke of the crosshead engage the shoulder 142 and lift the brush-carriers with them. Each bottom operating device, whether clamp or brush, is provided with a projection or stop 145 which is in position 40 to be engaged by a rod 133 (see Fig. 9). When a rod 133 engages a stop, the lower end of said rod rocks the lever 134 on its shaft 136, throws the projection 137 out of engagement with projection 138, whereupon 45 a spring 146, which is connected at one end to lever 134 above the pivot 140 of the trip-lever 139 and at its other end to the brush carrier frame, rocks said lever 134 and lever 139 and moves the shoulder 142 out of engagement with the pin 144. The trip levers 139 are connected to the shafts 136 by means of set-screws 136^a and move with said shafts. As soon as the projection 137 drops below 50 projection 138, the spring 146 rocks the trip lever to the left, through its connection with lever 134, breaks the connection between the pin 144 and the brush-carrier frame and, for the remainder of its upward stroke, the crosshead is disconnected from the brush-carrier frame. The brush-carrier remains in this position through frictional engagement with its guide rods, until it is engaged and lowered by pins 144 projecting from the crosshead, on the downward movement 55 of the latter.

It will be apparent, from this construction, that bottles of different sizes may be employed with my apparatus and that the brush and rinser spindles that coöperate therewith will be advanced inside the bottles a distance proportional to the length thereof, without liability to injure or break the bottles. On the down stroke of the crosshead, the pin 144 engages the rear end of the outwardly projecting shoulder 143 and, owing 70 to the location of the pivot 140, rocks said latch in a direction to bring the parts 137, 138 into engagement once more, whereupon the brush or rinser spindle and the carrier are in condition for another operation. It 75 will be observed that the space between shoulders 142 and 143 is considerably in excess of the width of the pin 144, whereby lost-motion is permitted of said pin with reference to said shoulders. This gives time 80 between the down stroke and the beginning 85 of the up stroke of the crosshead for locking the parts together.

The construction for operating the brackets 100, 100^a to bring the devices carried thereby into engagement with the bottoms of the bottles will now be described.

147 denotes a lever in the shape of a yoke the opposite arms of which are pivoted at their extremities to the opposite side of the frame 1. This yoke is provided with a central arm 148 projecting rearwardly therefrom and having at its end a roller 149 adapted to be engaged by a cam 150 carried by the shaft 30. The lever 147 is provided with rods 151 pivotally connected thereto and projecting upwardly therefrom. Each of these rods is connected at its upper end to an arm 152, which arms are adjustably secured to said rods by means of lock 100 nuts 153.

154 denotes a rod projecting vertically upward from each arm 152, being adjustably secured thereto by nuts 155. Each rod is forked at its upper end and is connected 110 to a lever 156, pivoted on a rod 156^a supported by the side frames 2. The opposite end of each lever 156 is connected by means of a link 157 to a crosshead 158. This crosshead is mounted on the rods 99 and slides freely 115 thereon. It is provided with two pairs of lugs 159 projecting rearwardly therefrom, said lugs corresponding in position to the rods 99 which are at the rear of the spindles 40 and 45. Between each pair of lugs 120 there is secured a cam 160. Each cam extends downwardly along the rear of a guide rod 99 and is adapted to operate the jaws for the purpose of opening the same in the following manner:—161 denotes lugs which 125 project upwardly from member 3 and are each provided with apertures 162 for the reception of the guide rods 163 of plungers 164. Each plunger has a front face which is adapted to engage a roller 95; also in- 130

clined faces on each side of the front face. The rods 163 merge at the rear of guide rods 99 and the rods corresponding to the first and third rods 99 are each provided at their junction with a roller 165. The rods at the second and fourth guide rods are connected by a plate 163^a.

166 denotes a rod projecting rearwardly from the end of each plunger through a lug 167 projecting upwardly from the plate 3. This rod is provided with a head at its rear end and with a spring 168 surrounding the same and extending between the lug 167 and the rear end of the plunger. The springs 168 are sufficiently stronger than the springs 93 to force the rollers 95 forwardly and close the jaws 91 around a bottle that may be in alinement with any one of the bottom-operating devices, thereby centering the bottles with respect to said devices before the engagement of a bottom-operating device therewith.

As will appear from an inspection of Fig. 17, the forward end of the plunger is inclined, whereby, as the carrier brings a pair of jaws opposite said plunger, the roller 95 may be pushed forwardly by its impact against the inclined side or cam of the plunger to close the jaws. As the springs 168 are stronger than the springs 93, it follows that the jaws which are opposite the second and fourth rods 99 and the plungers associated therewith will be held closed. For the purpose of allowing the side brushes 111, 112 to operate upon the outer surfaces of the bottles without any hindrance from the jaws, the particular construction of plungers shown at the first and third guide rods 99 is employed, together with the cams 160. As the cross-head 158 descends by its own gravity, the brackets 100, 100^a will descend in like manner, their locks being kept out of operation by said crosshead, until their respective bottom-operating devices are in contact with the bottoms of the bottles thereunder. Further downward movement of crosshead 158 causes the cams 160 to engage the rollers 165 and move the plungers 164 rearwardly, thereby subjecting the jaws 91 to the opening action of the springs 93. While the cams 160 are in operative relation to rollers 165, the jaws 91 are held open, and the operation of the side brushes 111, 112 will not be interfered with by said jaws. When the crosshead 158 is elevated a sufficient distance, these jaws will again be closed through the action of springs 168. Thus the jaws of all the clamps that are brought opposite the rods 99 are closed around the bottles by means of the plungers which, being yieldingly supported, will not cause the clamps to break the bottles. All the clamps center their bottles, the clamps corresponding to the bottom brushes remain-

ing closed during the operation of said brushes, while the clamps corresponding to the side brushes are opened by the cams 160 to allow the bottles to be rotated by the bottom clamps and permit the brushes 111 and 112 to have free access to the surfaces thereof.

As will appear from Fig. 4, a suitable number of springs 169 are interposed between the plate 6 and plate 125 which tend to lift said plate and the brush sleeves 56 upwardly into engagement with the bottoms of the sleeves 82. As will appear from Fig. 8, each brush sleeve 56 is provided with an outwardly tapering surface 56^b which is adapted to wedge into engagement with a corresponding surface on the gear hub 55. By means of a suitable lock disk 170, the downward movement of plate 125, which is produced toward the end of the down stroke of the crosshead 126 and rods 133, is communicated to the brush sleeve 56. This downward movement of plate 125 is accomplished by the heads upon the upper ends of the rods 133 engaging the upper surface of said plate, and the head upon the lower end of said rod being engaged by the brush-carrier draws the plate 125 to its normal position through said rod 133. This downward movement of each sleeve 56 causes the sleeve to be wedged into engagement with the hub 55 of its corresponding gear whereby said brush sleeve will be rotated by said corresponding gear at the time that the brush is withdrawn into the interior of said sleeve, thereby turning said sleeve with and at the same rate of speed as the spindle and prolonging the life of the brush.

With the parts arranged as described hereinbefore, the operation will be as follows: The movement imparted to the shaft 11 by the motor 9 is transmitted by belt 15 and pulleys 12 and 13 to the shaft 14; thence, by the train of reduction gearing 19, 20, 23, 24, 26, 27, gears 28, 29, shaft 30, gears 31, 32, 34, 35 to shaft 36 by means of which the bottle-bottom clamps and the bottom brushes are rotated. Furthermore, by means of shaft 18 and gears 58, 59, 60, 64, 65, 55^a and 68 the rotation of shaft 11 is imparted to the brush spindles. The gearing is so proportioned as to secure a high rate of revolution for the brush spindles. I have found the rate of 1500 revolutions per minute to be efficient for the brush spindles and a rate of about 60 revolutions per minute to be efficient for the bottom clamps and bottom brushes. The movement of shaft 36 is transmitted by means of the Geneva movement, shaft 71, gears 72 and 73 to the shaft 74 which operates the sprockets 75, 76, 78 and 79 for the bottle carrier. The operator, standing at the rear of the machine, inserts the bottles between the gripper jaws with

the mouths of the bottles resting in the mouth-supports 81. For every revolution of shaft 36, the carrier is advanced one step, or the distance between two of the mouth supports thereon. Also, for every revolution of shaft 30 the crosshead or frame 126 is given one vertical reciprocation, carrying with it the brush spindles 66, 67 and 69 and the rinser spindle 70. Also, by means of the 5 cam 150, the yoke lever 147 is depressed, thereby elevating the crosshead 158 and the brackets 100, 100^a to permit the bottles to be carried beneath their respective bottom-operating devices as well as to be shifted from 10 one such device to another. Before the completion of the revolution of shaft 30, the cams 160, in descending, open the jaws 91 of the grippers or clamps which hold the bodies of the bottles while being operated upon by 15 the side brushes 111, 112. The grippers or clamps will be left in open position (as shown in Fig. 13) opposite said brushes 111, 112 (after having first closed to center the bottles) so as not to interfere with the operation of the brushes upon the bodies of the 20 bottles, but will be closed on the bodies of the bottles while the bottles are operated upon by the bottom brushes. As the crosshead 126 is carried upwardly, it carries with it the brush and rinser spindles 66, 67, 69 and 70. With bottles of standard or greatest lengths 25 for which the machine is designed, the brush and rinser spindles will not come in contact with the bottoms of the bottles. When operating upon shorter bottles, the rods 133 will contact with their respective stops 145^a, and thereby trip the brush and rinser spindle carriers in the manner hereinbefore described before damage can be done to the 30 bottoms of the bottles by the upward movement of said spindles. The brackets 100, 100^a descend by gravity as soon as their locking members are disengaged by means of the 35 projections 159 and 171 on crosshead 158 and 40 continue to descend until the bottom brushes or the bottom clamps engage the bottoms of the bottles which have been inserted into the carrier by the operator. The bottom brushes will be provided each with a pin 114^a projecting downwardly from its brush head 114 and adapted to engage the bottoms of the 45 bottles which may be subjected to the action of the brushes and prevent further downward movement of their respective brackets. 50

As previously explained, the bottom clamps are rotated, whereby the bottles are thus rotated between the top and bottom clamps or supports therefor during the first and third operations to which the bottles are 55 subjected. The upward movement of the plate 125 under the influence of its springs 169 causes the conical ends 56^a of the brush sleeves to engage the bottoms of the mouth supports 81 and form a continuous passage- 60 way therewith for the passage of the brush 65

spindles into the interiors of the bottles. As previously explained, when the brush spindles are withdrawn into the sleeves 56, the inclined surfaces 56^b of such sleeves wedge against the hubs 55 of the gears 55^a, whereby said sleeves are rotated in the same direction as the brush spindles to prevent injury to the brushes when they are withdrawn from the bottles. 70

The bottles, in passing through my apparatus, are subjected first to an outside and inside brushing, second, to an inside and bottom brushing, third to an outside and inside brushing, fourth, to a rinsing and bottom brushing operation. After being subjected 75 to the last operation, the bottles are carried out into the free space beyond the casing 7 and may be removed by the operator. 80

In Figs. 11 and 13 there are shown details of the bottoms of the brush and rinser spindle supports. Each support is provided with a hose or similar flexible connection 172 connected to a chamber 173 in the bottom of each of said supports. A bushing 174 surrounds the lower portion of each brush 90 spindle and is threaded into the top of the support. At its bottom, each rinser spindle is provided with a thrust collar 175, which is in the shape of a double cone fitting the correspondingly shaped interior chamber 95 173. 176 denotes a lock nut for securing the bushing 174 in place. The bushing is tapered on its lower surface to correspond to the inclination of the upper surface of the thrust collar 175, and a packing 177 is interposed between said surfaces. The flexible 100 hose or pipes 172 may be supplied from a common pipe 178 (see Fig. 4). The rinser spindle 70 is similar to the spindles 67 but has no gear for rotating the same and is 105 fitted to its support by means of a bushing 179 into which it is threaded. This bushing is provided with a lock nut 180. No thrust collar is necessary for the rinser spindle as it does not rotate. The spindle is provided 110 with a vertical port 181 in the top thereof and with downwardly inclined lateral ports 182 therebeneath. 115

Having thus described my invention, I claim:

1. In a bottle cleaning apparatus, the combination of a bottle carrier, means for imparting movement to said carrier, operating devices for the bottoms of bottles interposed in the path of movement of said carrier, means for bringing said devices into engagement with the bottoms of bottles which are moved into operative relation thereto by the carrier, a cleaning device for each bottle which is in operative relation to one of the former devices, means whereby the cleaning device may be moved, and means independent of the bottle for automatically limiting said movement according to the length of the bottle. 120

2. In a bottle cleaning apparatus, the combination of a bottle carrier, means for imparting movement to said carrier, bottle-operating devices interposed in the path of movement of said carrier, means for automatically bringing said devices into engagement with the bottles which are moved into operative relation thereto by the carrier, a cleaning device for the interior of each 10 bottle which is in operative relation to the former devices, means whereby the cleaning device may be moved, and means independent of the bottle for automatically limiting said movement according to the distance through which said device can pass without 15 obstruction.

3. In a cleaning apparatus for bottles of varying lengths, the combination of a bottle support, a device for cleaning the interior 20 of a bottle on said support, means whereby the cleaning device may be moved, and means independent of the bottle for automatically limiting said movement according to the distance between its starting point and an 25 obstruction provided by the bottle.

4. In a cleaning apparatus for bottles of varying lengths, the combination of a bottle support, a device for cleaning a bottle on said support, means whereby the cleaning 30 device may be moved, and means independent of the bottle for automatically limiting said movement according to the length of the bottle.

5. In a bottle cleaning apparatus, the combination of a plurality of bottle supports, a plurality of cleaning devices corresponding 35 to said supports, a carrier for each of said devices, a frame common to all of said carriers, means for reciprocating said frame toward and from the bottle supports, and 40 breakable connections between said frame and said carriers.

6. In a bottle cleaning apparatus, the combination of a plurality of bottle supports, a 45 cleaning device corresponding to each of said supports, a carrier for each of said devices, a frame common to all of said carriers, means for reciprocating the frame, a connection between said frame and each of said 50 carriers, and means whereby the connection between each of said carriers and said frame may be automatically broken when a carrier has been moved less than a predetermined distance toward its bottle support.

55 7. In a bottle-cleaning apparatus, the combination of a bottle support, a cleaning device, a carrier therefor, a movable member, means for reciprocating the same toward and from the bottle support, a connection 60 between said carrier and said member, said connection including a tripping device, and means associated with the carrier and adapted to engage a projection on the bottle support to operate the tripping device and

break the connection between the carrier and 65 the movable member.

8. In a bottle-cleaning apparatus, the combination of a plurality of bottle supports, bottle-cleaning devices corresponding to said supports, a carrier for each of said 70 devices, a crosshead or frame, means for reciprocating the same toward and from the supports, connections including a trip device between each of said carriers and said crosshead or frame, and means for operating 75 said trip device to break the connection between a carrier and the frame when the latter is moved less than a predetermined distance toward a bottle support.

9. In a bottle-cleaning apparatus, the combination of a plurality of bottle supports, a plurality of bottle-cleaning devices corresponding thereto, a carrier for each of said devices, a frame or crosshead, means for reciprocating the same toward and from the 80 bottle supports, a lost-motion connection between said frame and each of said carriers, and means for automatically breaking said connections when the carrier has been moved less than a predetermined distance toward 85 the bottle support.

10. In a bottle-cleaning apparatus, the combination of a plurality of bottle supports each comprising a member adapted to engage the bottom of a bottle, a cleaning 90 device corresponding to each of said supports, a carrier for each of said devices, a frame common to all of said carriers, means for reciprocating said frame, and a member 95 on each of said carriers adapted to engage the bottom member of each bottle support and thereby break the connection between said carrier and the frame.

11. In a bottle-cleaning apparatus, the combination of a plurality of bottle supports, said supports comprising each a member adapted to engage the bottom of a bottle, a cleaning device corresponding to said supports, a carrier therefor, a frame, means for moving the same toward and from the 100 bottle supports, a breakable connection between each of said carriers and said frame, said means comprising a trip device, a member adapted to engage said device, a spring tending to operate the trip device to break 105 the connection between the same and said member, a lever normally locking said device against movement by the spring, a rod on the carrier having an end engaging said lever, and a stop on the bottle-engaging 110 member adapted to engage said rod and thereby operate the lever to subject the tripping device to the action of the spring.

12. In a bottle-cleaning apparatus, the combination of a bottle support, a cleaning 115 device, a carrier for said device, a frame, means for reciprocating said frame, a connection between said frame and said car-

rier, said connection comprising a pivoted trip-device having a pair of shoulders, a pin carried by the frame and projecting between said shoulders, a spring connected 5 with said trip-device and tending to move the same in a direction to break the connection between the pin and said device, a lever pivoted to said device and having a projection, a projection on the carrier adapted 10 to engage the projection on the lever and thereby block the movement of the trip device by the spring, an arm on said lever, a rod on said carrier having an end supported by the lever arm, and a projection adapted 15 to engage said rod and thereby operate said lever when the carrier has been moved less than a predetermined distance by its frame.

13. In a bottle-cleaning apparatus, the 20 combination of a bottle support, a cleaning device, a carrier for said device, a frame, means for reciprocating said frame, a connection between said frame and said carrier, said connection comprising a pivoted trip 25 device having a pair of shoulders, a pin carried by the frame and projecting between said shoulders and forming a lost-motion connection therewith, a spring connected with said trip device and tending to move 30 the same in a direction to break the connection between the pin and said device, a lever pivoted to said device and having a projection, a projection on the carrier adapted to engage the projection on the lever and thereby 35 block the movement of the trip device by the spring, an arm on said lever, a rod on said carrier having an end supported by the lever arm, and a projection on the bottle support adapted to engage said rod and thereby 40 operate said lever when the carrier has been moved less than a predetermined distance by its frame.

14. In a bottle-cleaning apparatus, the 45 combination of a bottle support, a bottle-cleaning device, means for moving the same toward and from a bottle, and a breakable connection included in said means.

15. In a bottle-cleaning apparatus, the 50 combination of a bottle support, a bottle-cleaning device, a support therefor, and mechanism for moving the latter support toward the former a distance proportional to the distance of a bottle and from the latter support.

55 16. In an apparatus for cleaning bottles of varying lengths, the combination of a bottle support, a device for cleaning the interior of a bottle on said support, and means for moving said device into the interior of a bottle on said support a distance proportional to the length of the distance between the mouth and bottom.

17. In an apparatus for cleaning bottles of varying lengths, the combination of a bottle

support, a brush for the interior of a bottle 65 on said support, means for moving the brush toward the bottom of a bottle on said support, and means for automatically suspending the operation of the latter means when the brush is in proper presentation to the 70 bottom of the bottle.

18. In a bottle-cleaning apparatus, the combination of a bottle support, a brush for the interior of a bottle on said support, a device for reciprocating said brush, and means 75 whereby the movement of the said device toward the bottom of a bottle may be automatically suspended before the end of the stroke of the reciprocating means.

19. In a bottle-cleaning apparatus, the combination of a carrier having thereon a plurality of bottle supports, a member adapted to engage the bottoms of bottles on said carrier, a device, corresponding to said member, for cleaning the interiors 85 of the bottles on the carrier, means for reciprocating said cleaning device, mechanism whereby the reciprocation of the cleaning device may be automatically varied according to the amount of open space existing 90 between the mouth and bottom of a bottle engaged by said member, and means for moving said carrier intermittently to bring the bottles thereon successively to the bottom-engaging member. 95

20. In a bottle-cleaning apparatus, the combination of a carrier, bottle supports thereon, means for imparting movement to said carrier, a plurality of devices for the bottoms 100 of the bottles on said carrier, a bracket for each of said devices, a guide rod for each bracket, an automatic locking device carried by each bracket for retaining a bracket and its device on a guide rod, and means for automatically raising said brackets and the devices thereon out of engagement with the bottoms of bottles and for lowering the same to bring the devices into engagement with the bottoms of the bottles on the carrier. 105

21. In a bottle-cleaning apparatus, the combination of a carrier having thereon a plurality of bottle supports, means for imparting movement to said carrier, a series of vertically reciprocable bottle clamps, means for automatically lowering and raising the 110 clamps to bring the same into and out of engagement with the bottles on the carrier, and an automatic locking device for each of said clamps adapted to retain the clamp in any position in which it may be left by its 115 operating means.

22. In a bottle-cleaning apparatus, the combination of a bottle carrier, means for imparting movement thereto, an operating device for the bottles on said carrier, said device comprising a bracket, a pivoted locking member carried by said bracket, a guide rod 125 on which said bracket is mounted, a spring

tending to force said member into engagement with the guide rod, and an operating member for said bracket, said member having a projection adapted to engage the locking member and move the same against the action of the spring to unlock the bracket from the guide rod.

23. In a bottle-cleaning apparatus, the combination of a bottle carrier, means for imparting intermittent movement thereto, a bottle-bottom brush, a casing surrounding said brush and fixed in position relatively to said brush, means for simultaneously moving said brush and casing into a position allowing said brush to operate upon the bottoms of bottles brought into operative relation thereto by the carrier, means for rotating said brush and casing, and connections for supplying water to said casing.

24. A brush for the bottoms of bottles comprising a perforated casing adapted to receive the bottom of a bottle therein, a brush head within said casing, a shell within which said casing is rotatably mounted, means for rotating said casing and said brush head, and connections for supplying water to the interior of the shell and thence through the perforations in the casing.

25. A bottom brush for bottle-cleaning apparatus comprising a brush head, a casing inclosing the same and movable therewith, a bracket having a sleeve or shell for said casing, an anti-friction bearing between said casing and said shell, a cap mounted on the shell of said bracket, connections for supplying water to the space below the said cap, and means for rotating the casing and the cap.

26. A brush for the bottoms of bottles comprising a brush head having a pin projecting therefrom, a casing inclosing said brush head and provided with perforations, said casing being open at its lower end, an adjustable bracket having a shell or sleeve surrounding the casing and extending thereabove, a cap resting on said shell or sleeve, connections for supplying water to the space below said cap, and an antifriction bearing between the lower end of the shell and the lower end of the casing.

27. A bottom brush for bottles comprising a brush head, a casing inclosing the same and movable therewith, a sleeve or shell for said casing, an anti-friction bearing between the bottom of said casing and said shell, a cap mounted on the shell, connections for supplying water to the space between the casing and the shell, and means for rotating the casing and the cap.

28. In a bottle-cleaning apparatus, the combination of a carrier, said carrier having mouth supports for the bottles thereon and grippers for the bodies of the bottles thereon, a series of operating devices for the bottles on the carriers, said operating de-

vices comprising a side brush and a bottom brush, a bottom clamp coöperating with the side brush, means for operating the carrier to bring the bottles thereon successively into operative relation to the said brushes, and means for bringing the clamp and the bottom brush into engagement with the bottles on the carrier.

29. A bottle-cleaning apparatus comprising an upper and a lower chain having bottle-supporting brackets, each bracket having mounted thereon a pair of gripper jaws and a bottle mouth support.

30. A bottle-carrier comprising an upper and a lower chain, said chains carrying vertically extending brackets, each bracket being provided with an outwardly projecting portion provided with an aperture for a bottle mouth support and with a gripping device for the body of a bottle.

31. A bottle-carrier comprising an upper and a lower chain having brackets connected thereto, each bracket having a bottle mouth support and a pair of bottle-gripping arms, and springs tending to open said arms.

32. In a bottle-cleaning apparatus, the combination of a bottle-carrier, a pair of devices for operating in series on the bottles on the carrier, one of said devices comprising a side brush for the bottles on the carrier, a body-clamp for the bottles on the carrier, means for moving the carrier to subject the bottles thereon successively to the operating devices, and means for opening the clamp when the bottles are brought in operative relation to the side brush.

33. In a bottle-cleaning apparatus, the combination of a bottle-carrier, a plurality of devices for operating upon the bottles on said carrier, each of said devices comprising a member adapted to engage the bottom of a bottle on the carrier, a bracket for each of said devices, guide rods for said brackets, means tending to lock each of said brackets to a guide rod, a crosshead mounted on said guide rods beneath said brackets and provided with means for engaging the locking devices on the brackets to prevent the operation thereof, means for reciprocating the crosshead, and means for imparting movement to the carrier.

34. In a bottle-cleaning apparatus, the combination of a bottle-carrier, a plurality of devices for operating upon the bottles on said carrier, guide rods for said devices, means for holding the guide rods, means tending to lock each of said devices to a guide rod, a crosshead mounted on said guide rods and provided with means for engaging the locking devices to prevent the operation thereof, means for reciprocating the crosshead, and means for imparting movement to the carrier.

35. In a bottle-cleaning apparatus, the combination of a bottle carrier, said carrier

having clamps for the bodies of the bottles thereon, a plurality of devices adapted to operate upon the bottles on said carrier, a bracket for each of said devices, a guide rod 5 for each of said brackets, means tending to lock each of said brackets to its rod, a cross-head common to said brackets and adapted to engage the locking means to prevent the operation of the same, one or more clamp-operating means carried by said crosshead, means for reciprocating said crosshead, and means for imparting movement to the carrier.

36. In a bottle-cleaning apparatus, the combination of a bottle carrier, said carrier having clamps for the bodies of the bottles thereon, a plurality of vertically reciprocable devices adapted to operate upon the bottles on said carrier, a frame common to 20 said devices and adapted to prevent the operation of the locking means therefor, one or more clamp-operating means carried by said frame, means for reciprocating said frame, and means for imparting movement 25 to the carrier.

37. In a bottle-cleaning apparatus, the combination of a carrier having thereon a plurality of body clamps for bottles, each clamp comprising a pair of jaws, means 30 tending to open said jaws, a series of operating devices for the bottles on the carrier, clamp-operating means associated with one or more of said devices and arranged to close the jaws of a clamp, and means for 35 imparting movement to the bottle carrier.

38. In a bottle-cleaning apparatus, the combination of a carrier having thereon a plurality of body clamps for bottles, each clamp comprising a pair of jaws, means 40 tending to open said jaws, a series of operating devices for the bottles on the carriers, clamp operating means associated with said devices, the clamp operating means at all of said devices being arranged to close 45 the jaws to center the bottles therebetween, means at some of said devices for thereafter opening the jaws of the clamps associated therewith, and means for operating the bottle carrier.

50. 39. In a bottle cleaning apparatus, the combination of a carrier having thereon a plurality of bottle clamps, each clamp comprising a pair of pivoted jaws each having an operating arm projecting beyond the 55 pivot thereof, toggle links connecting said arms, a spring tending to force the jaws in one direction, a roller at the joint formed between the toggle links, a series of operating devices for the bottles on the carrier, 60 a spring-pressed plunger associated with each of said devices and adapted to engage the rollers to force the jaws in the opposite direction from the spring associated therewith, and means for imparting movement 65 to the carrier.

40. In a bottle-cleaning apparatus, the combination of a bottle-carrier, said carrier having thereon a plurality of clamping devices for bottles, each clamping device comprising a pair of pivoted jaws and a spring 70 tending to force the same in one direction, a plurality of operating devices for the bottles on the carrier, each device having associated therewith a member adapted to operatively engage the clamps and operate 75 the same in a direction the reverse of that of the spring connected thereto, and means for imparting movement to the carrier.

41. In a bottle-cleaning apparatus, the combination of a bottle-carrier, said carrier having a plurality of clamps, each clamp comprising a pair of pivoted jaws and means tending to operate the same in one direction, a plurality of operating devices for the bottles on the carrier, each of 80 said devices having associated therewith means adapted to operatively engage the clamps and move the same in a direction opposite that given by the means associated therewith, mechanism for automatically operating some of the last-mentioned means to release the clamps to the action of their operating means, and means for imparting movement to the carrier.

42. In a bottle-cleaning apparatus, the combination of a bottle carrier having a plurality of bottle clamps thereon, each clamp comprising a pair of jaws and a spring tending to move the same in one direction, a plurality of devices for operating upon the bottles in the carrier, each of said devices having associated therewith a spring-pressed plunger adapted to engage the clamps in succession and operate the same 95 against the action of its spring, a side brush associated with one of the bottle-operating devices, and means for automatically moving the spring-pressed plunger associated with such device away from the clamps that may be brought into operative relation to 100 said brush to thereby subject the clamps to the action of its spring, and means for imparting movement to the carrier.

43. In a bottle-cleaning apparatus, the combination of a carrier having thereon a 115 plurality of clamps for the bodies of bottles, a plurality of operating devices to which the bottles on the carrier are successively subjected, one of said devices comprising a rotary side brush, means associated with said device for automatically opening the bottle clamps to prevent interference with the action of the side brush by said clamps, and means for imparting movement to the carrier.

44. In a bottle-cleaning apparatus, the combination of a carrier having thereon a plurality of clamps for the bodies of bottles, means tending to open each of said clamps, a plurality of operating devices to which 130

the bottles on the carrier are successively subjected, one of said devices comprising a rotary side brush, means associated with each device for automatically closing the 5 bottle clamps to center the bottles on the carrier, means associated with the side brush device for thereafter suspending the operation of the clamp-opening means, and means for imparting movement to the carrier.

45. In a bottle-cleaning apparatus, the combination of a bottle carrier, means including body clamps for supporting bottles on said carrier, an operating device for the bottles on the carrier, means associated with 10 said device for operating said body clamps, and means for moving said carrier so as to present successive bottles to the operation of the cleaning means.

46. In a bottle-cleaning apparatus, the combination of a bottle carrier, means including body clamps for supporting bottles on said carrier, a bottle-rotating device and a bottle-bottom brush arranged in series, a clamp-operating device associated with said 25 brush, both of said clamp-operating devices being arranged to close the clamps about their respective bottles, means for automatically opening the clamp for the bottle which is subjected to the action of the rotating device, and means for moving the carrier so as to present successive bottles to the operation of the cleaning means.

47. In a bottle-cleaning apparatus, the combination of a carrier, means for supporting thereon bottles in an inverted position, said means comprising a bottle mouth support having a downwardly projecting sleeve, a plurality of brush spindles, means for imparting movement to the carrier to 30 bring the bottles thereon successively above said brush spindles, a sleeve for each of said spindles, means for rotating each of said spindles, means for reciprocating said spindles, and connections whereby the brush 40 sleeve will be rotated on the withdrawal of the spindles from the bottles.

48. In a bottle-cleaning apparatus, the combination of a brush sleeve having a tapered upper end, a carrier having a bottle- 50 mouth support, means tending to force the brush sleeve into engagement with the bottle-mouth support, a brush and spindle reciprocable in said sleeve, a gear on said spindle having a hub surrounding said brush 55 sleeve, means for rotating said gear, connections for locking together the brush sleeve and the gear hub by the withdrawal of the brush into the brush sleeve, and means for imparting movement to the carrier.

49. In a bottle cleaning apparatus, the combination of a plate, a plurality of brush sleeves carried thereby, a bottle carrier having a plurality of bottle-mouth supports thereon, means for imparting movement to

the carrier to bring the bottle-mouth supports in operative relation to the brush sleeves, springs forcing the plate toward the bottle mouth supports, a plurality of brush spindles for said sleeves, means for reciprocating said spindles through said sleeves, 65 means for rotating said spindles, connections for moving the plate and brush sleeves downwardly by the withdrawal of the spindles from the mouth supports, and means for connecting the brush sleeves with the spindle-rotating means by the movement of the sleeves away from the mouth supports.

50. In a bottle-cleaning apparatus, the combination of a bottle-support, a brush sleeve, a brush spindle having a brush thereon, means for reciprocating the brush and spindle through the brush sleeve, means for rotating the brush spindle, and connections whereby the withdrawal of the brush into the sleeve will connect said sleeve with the spindle rotating means.

51. In a bottle-cleaning apparatus, the combination of a brush sleeve having a tapered upper end, a carrier having a bottle-mouth support, means tending to force the brush sleeve into engagement with the bottle mouth support, a brush and spindle having a hub surrounding said brush sleeve, means for rotating said gear, connections for locking together the brush sleeve and the gear hub by the withdrawal of the brush into the brush sleeve, and means for imparting movement to the carrier.

52. A bottle carrier comprising an upper and a lower chain having brackets connected thereto, each bracket having a bottle mouth support and a pair of bottle gripping arms, and springs and cams tending one to open said arms and the other to close 100 said arms.

53. In a bottle cleaning apparatus, in combination, a device for supporting a bottle in inverted position and moving same horizontally, a cleaning device over which said support is adapted to be moved, and with which it is adapted to be aligned, a carrier for said cleaning device, a cross head adapted to be moved toward and from said bottle support, and a breakable connection between said carrier and cross head.

54. In a bottle cleaning apparatus, in combination, a plurality of spaced bottle supports, a plurality of cleaning devices with which said bottle supports are adapted to be brought into register, said supports and cleaning devices being spaced apart the same distances, a carrier for each of said cleaning devices, each of said carriers being arranged for movement toward and from the support opposite thereto whereby the corresponding cleaning device can be inserted into and withdrawn from the corresponding bottle, movable means for actuating

ing said carriers, and breakable connections between said movable means and said carriers and arranged to release said carriers upon contact with an obstruction.

- 5 55. In a bottle cleaning apparatus, the combination of a bottle support, a device for cleaning the interior of a bottle on said support, a carrier for said cleaning device, means for moving the carrier toward and 10 from said support, and a breakable connection between said carrier and said moving means arranged to disengage said carrier upon encountering an obstruction.

56. In a bottle cleaning apparatus, the 15 combination, with means for supporting a bottle in an inverted position and moving the same horizontally, of an upright guideway over which said bottle is adapted to be brought, a carrier slidable along said guideway, a device mounted on said carrier and adapted to be inserted into said bottle to 20 clean the interior thereof, a cross head movable along said guideway, means for moving said cross head first toward and then away 25 from said bottle support, and a breakable connection between said carrier and cross head arranged to become disconnected on the upward movement in case of contact with an obstruction and to become automatically 30 reconnected upon the downward movement.

57. In a bottle cleaning apparatus, in combination, a bottle carrier, a rotatable sleeve past which a bottle on said carrier is adapted to be moved and with which it is 35 adapted to be alined, means for rotating said sleeve, an elongated shaft coaxial with said sleeve, means engaging said shaft and sleeve and permitting relative longitudinal movement while preventing relative rotary 40 movement, a brush carried by the end of said shaft, a second sleeve concentric with said shaft and introduced between said brush and said first sleeve, means whereby said second sleeve is journaled, means op- 45 erative for advancing said second sleeve toward a bottle presented by said carrier, means for thereafter advancing said brush into said bottle, and means for thereafter withdrawing said brush and sleeve.

50 58. In a bottle cleaning apparatus, in combination, a device for supporting a bottle in an inverted position and moving the same horizontally, a cleaning device over which said support is adapted to be moved and 55 with which it is arranged to be alined, a bearing plate adjacent to the path of movement of said bottle support, a rotatable sleeve journaled in said bearing plate and adapted to be brought into alinement with 60 a bottle on said carrier, a second sleeve telescopically engaging said first sleeve, a brush shaft telescopically engaging said second sleeve, a brush carried by said shaft inside said first sleeve, means for rotating said

sleeves and shaft, mechanism adapted to reciprocate said plate toward and from said carrier, said mechanism being arranged to provide a dwell between the advancing and retreating movements of said plate, and means for advancing said brush beyond said sleeve and into said bottle and for withdrawing the same from said bottle into said sleeve during said period of dwell. 65

59. In a bottle cleaning apparatus, in combination, a device for supporting a bottle in inverted position and moving same horizontally, an upright guideway over which said support is adapted to be moved, a bearing plate slidably carried by said guideway, an upright sleeve journaled in said bearing plate and arranged to be brought into alinement with a bottle on said carrier, a second sleeve with which said first sleeve telescopes, yielding means tending to elevate said plate, means operative at predetermined intervals 80 to permit the upward movement of said plate whereby said first sleeve is advanced to form a closed conduit communicating with the bottle on said carrier, cleaning devices in said sleeve adapted to operate upon 85 the bottle interior during the continuation of such communication, and means for thereafter depressing said plate and withdrawing said sleeve. 90

60. In a bottle cleaning apparatus, in combination, a device for supporting a bottle in inverted position and moving same horizontally, a guideway over which said support is adapted to be moved, a carrier slidably mounted on said guideway, a rotatable shaft swiveled to said carrier, a bearing plate mounted for movement parallel to said guideway, a sleeve rotatably mounted in said bearing plate concentric with said shaft, a second rotatable sleeve fixed with reference to said guideway and with which said first sleeve and said shaft telescope, a brush carried by said shaft inside said first sleeve, yielding means associated with said plate and tending to raise the same, means operative upon the movement of a bottle station into alinement therewith for permitting the rising of said plate whereby said first sleeve is advanced to form a closed conduit communicating with the mouth of 115 the bottle in said station, means for thereafter advancing said brush into the bottle and withdrawing it therefrom; means for rotating said shaft and sleeves, and means for withdrawing said plate from the bottle 120 after the withdrawal of said brush.

61. In a bottle cleaning apparatus, in combination, a device for supporting a bottle in inverted position and moving same horizontally, an upright guideway over which 125 said support is adapted to be moved, a bearing plate mounted for movement parallel with said guideway, an upright sleeve jour-

naled in said bearing plate and arranged to be brought into alinement with a station on said carrier, a second sleeve with which said first sleeve telescopes, a cup shaped member 5 interposed between said sleeve and bottle and receiving the bottle mouth, means normally tending to advance said first sleeve so as to form a tight joint to the bottle mouth, a rotatable brush rotatably and translationaly mounted in said first sleeve, means for advancing said brush to cause it to operate upon the bottle interior, and means for withdrawing said sleeve prior to the removal of the bottle by said supporting device.

62. In a bottle cleaning apparatus, in combination, a device for supporting a bottle in inverted position and moving same horizontally, a guideway over which said support is adapted to be moved, a carrier slidably mounted on said guideway, a rotatable shaft swiveled to said carrier, a bearing plate mounted for movement parallel to said guideway, a sleeve rotatably mounted in said bearing plate concentric with said shaft, a second rotatable sleeve fixed with reference to said guideway and with which said first sleeve and said shaft telescope, a brush carried by said shaft inside said first sleeve, a cross head adjacent to said carrier and movable in a direction parallel therewith, means for reciprocating said cross head, breakable connections between said cross head and carrier and arranged to permit the separation of the same upon the advancing movement in case of contact with an obstruction, means for retracting said first sleeve toward the end of the retractive movement of said brush, means for advancing said sleeve together with the first part of the advancing movement of said brush, and means for rotating said shaft and sleeves.

63. In a bottle cleaning apparatus, in combination, a journal casting, a rotatable sleeve journaled therein, a pinion for rotating said sleeve, a second sleeve telescoped within said first sleeve, a plate in which said second sleeve is journaled, means for transporting bottles past said sleeve with their mouths presented thereto, yielding means operatively associated with said plate and tending to force the same toward said bottles, a rotatable shaft coaxial with said sleeves, said shaft being reciprocably but not rotatably connected to said first sleeve, a brush carried by the end of said shaft and normally withdrawn into said second sleeve, means arranged to release said plate upon the approach of a bottle thereto whereby said second sleeve may be advanced to form a closed conduit communicating with the bottle mouth, means for thereafter advancing said shaft to introduce said brush into the bottle, means for thereafter retracting

said shaft, and means for finally withdrawing said second sleeve from the bottle mouth.

64. In a bottle cleaning apparatus, in combination, a journal casting, a guide member secured thereto, a carrier movable upon said guide member, a sleeve journaled in said casting, a second sleeve telescoped in said first sleeve, a hollow shaft journaled to said carrier and extending into said sleeves, means for driving said shaft and sleeves, a brush carried by the end of said shaft and normally concealed within said second sleeve, a plate journaled to said second sleeve at the opposite side of said casting from said guide member, a bottle carrying device beyond said second sleeve and arranged to support bottles in alinement therewith and with their mouths presented toward the same, yielding means tending to move said plate toward said bottles whereby said second sleeve may form a closed conduit communicating with the mouth of said bottle, connections between said plate and said carrier whereby upon the retraction of said carrier said plate will be withdrawn from the bottles, and means for reciprocating said carrier whereby first, said sleeve will be permitted to approach the bottle, second, the brush will be inserted into the bottle, third, the brush will be withdrawn from the bottle, and fourth, said first sleeve will be withdrawn.

65. In a bottle cleaning apparatus, in combination, a journal casting, a guide member secured thereto, a hollow carrier movable upon said guide member, a sleeve journaled in said casting, a second sleeve telescoped in said first sleeve, a hollow shaft journaled to said carrier and extending into said sleeves, the interior of said shaft being in communication with the interior of said carrier, a flexible tube connected to said carrier and communicating with a source of liquid supply, a pinion carried by said first sleeve, a gear wheel carried by the machine and meshing with said pinion, a brush carried by the end of said shaft and normally concealed within said second sleeve, a plate journaled to said second sleeve at the opposite side of said casting from said guide member, a bottle carrying device beyond said second sleeve and arranged to support bottles in alinement therewith and with their mouths presented toward the same, yielding means tending to move said plate toward said bottles whereby said second sleeve may form a closed conduit communicating with the mouth of said bottle, connections between said plate and said carrier whereby upon the retraction of said carrier said plate will be withdrawn from the bottles, and means for reciprocating said carrier, whereby, first, said sleeve will be permitted

to approach the bottle; second, the brush will be inserted into the bottle, third, the brush will be withdrawn from the bottle, and, fourth, said first sleeve will be withdrawn to permit drainage from the bottle.

66. In a bottle cleaning apparatus, in combination, a reciprocable carrier, a rotatable shaft journaled to said carrier, a brush carried by the end of said shaft, a plate beyond said carrier and reciprocable in a direction parallel thereto, a rotatable sleeve journaled to said plate coaxial with said shaft and adapted to receive said brush, means for rotating said shaft and sleeves, a bottle carrier beyond said plate and arranged to support bottles in alinement with said sleeve and with their mouths presented toward said brush, means for forcing said plate yieldingly toward said bottles, whereby said sleeve may effect a closed conduit communicating therewith, connections between said plate and carrier whereby said sleeve will be withdrawn upon the retraction of said carrier, and means for retracting said carrier.

67. In a bottle cleaning apparatus, in combination, a journal casting, a rotatable sleeve carried thereby, means for rotating said sleeve, a carrier reciprocable toward and from said casting in a direction parallel to the axis of said sleeve, a rotatable shaft journaled to said carrier and projecting through said sleeve, said shaft being slidable relative to said sleeve but nonrotatable relatively thereto, a brush carried by the end of said shaft, a second sleeve between said first sleeve and said shaft and adapted to receive said brush, a plate journaled to said second sleeve upon the opposite side of said casting from said carrier, a rod connected to said plate and adapted to be engaged by said carrier upon the retraction of the same to draw said plate toward said casting, yielding means tending to move said plate away from said casting, a bottle carrier adapted to present bottles in alinement with said sleeves and with their mouths presented toward said brush, and means for reciprocating said carrier so as to advance and retract the same during the period that each bottle is so presented.

68. In a bottle cleaning apparatus, the combination, with a plurality of laterally spaced journal members, a rotatable sleeve carried by each member, a pinion carried by each sleeve, gearing arranged to rotate all said pinions, a carrier opposite each sleeve and reciprocable toward and from the same in a direction parallel to the axis of said sleeve, a rotatable shaft journaled to said carrier and projecting through said sleeve, said sleeve having its lower end constricted so as to embrace said shaft, and being non-rotatably interlocked therewith but slid-

able relatively thereto, a brush carried by the end of said shaft, a second sleeve between said first sleeve and said shaft and adapted to receive said brush, a member located beyond said second sleeve and having a cupped portion adapted to receive the mouth of a bottle, said last member having an aperture therethrough for the passage of said brush, means for holding a bottle in alinement with said shaft and with its mouth in said cup, reciprocable means adjacent to said carriers, and movable in a direction parallel to said shafts, mechanism for actuating said means toward and from said sleeves, and a breakable connection between said means and said carriers whereby said carriers will normally accompany said means but will become disengaged therefrom during the movement toward the sleeves upon encountering an obstruction, said breakable connection being arranged to be reestablished automatically upon the next return movement of said reciprocating means after the disconnection thereof.

69. In a bottle cleaning apparatus, the combination, with a supporting frame, a plurality of laterally spaced journal members carried thereby, a rotatable sleeve journaled in each member, a pinion carried by each sleeve, gearing carried by said frame and meshing with said pinions, a guide rod carried by each of said journal members and parallel with the axis of the corresponding sleeve, a carrier associated with each of said journal members and slidable along the corresponding guide rod, said carrier having a liquid passage therein, a hollow rotatable shaft, projecting through said sleeve, a fluid tight swivel joint whereby said shaft is journaled to said carrier, said shaft being slidable relatively to said sleeve but non-rotatable relatively thereto, a brush carried by the end of said shaft, a second sleeve between said first sleeve and said shaft and adapted to receive said brush, a plate journaled to said second sleeve upon the opposite side of said journal member from said carrier, a rod connecting said plate and carrier and adapted to be engaged by the latter upon its retraction whereby said plate will be drawn toward said journal member, yielding means tending to move said plate and second sleeve away from said journal member, a flexible tube communicating with the liquid passage in each carrier and adapted to deliver cleansing fluid to said brush, a bottle holder adapted to present bottles in alinement with said sleeves and with their mouths presented toward said brush, reciprocable means located adjacent to said carriers and movable parallel to said guide rods, mechanism for actuating said means toward and from said bottle holder, and a breakable connection between each carrier

and said reciprocable means whereby said carrier will normally accompany said means but will become released therefrom upon encountering an obstruction, said breakable connection being arranged to be reconnected automatically upon the reverse movement of said reciprocating means.

In testimony whereof, I hereunto affix my signature in the presence of two witnesses.

BRYAN D. PINKNEY.
